To all whom it may concern:

Be it known that I, LOUIS KRANZ, a citizen of the United States, residing at Providence, in the State of Rhode Island, have invented and produced a new and original Design for a Handle for Button-Hooks or Similar Articles, of which the following is a specification, reference being had to the accompanying drawings, forming part thereof.

As shown in the drawings, the leading and material features of my design consist in the circumferentially-beaded end *a*, the reverse-ly-foliated ornamentation *b*, the shield *c*, sur-

rounded by the foliated scroll *d*, the foliated scrolls *e* *e*, the flower *f* and the leaves *g*, the shield *h* and the flower *i*, having on one side the knurled foliated scroll *j* and on the other 20 the beaded foliated scroll *k* and the terminal shell ornament *m*.

Having now described my invention, what I claim as new, and desire to secure by Letters Patent, is—
